UNITED STATES PATENT OFFICE.

EDGAR H. FREEMAN, OF TRENTON, NEW JERSEY, ASSIGNOR TO E. H. FREEMAN ELECTRIC COMPANY, A CORPORATION OF NEW JERSEY.

SCREW-SHELL-CONTACT MOUNTING FOR ATTACHMENT-PLUGS.

1,373,127.

Specification of Letters Patent. Patented Mar. 29, 1921.

Application filed July 21, 1919. Serial No. 312,288.

To all whom it may concern:

Be it known that I, EDGAR H. FREEMAN, citizen of the United States, residing at Trenton, in the county of Mercer and State 5 of New Jersey, have invented certain new and useful Improvements in Screw-Shell-Contact Mountings for Attachment-Plugs, of which the following is a specification.

This invention relates to electric fittings 10 and has special reference to an improvement in attachment plugs.

A primary object of the invention is to provide a simple and practical means for holding the several electrical contact parts 15 of the plug securely in position. That is to say, the present invention proposes to provide a construction whereby the screw shell contact of the plug and one of the spring contact terminals thereof may be easily and 20 quickly assembled and secured in position. In this connection it is proposed to provide an arrangement of parts which permits of the fastening means being located at a point where the same will not engage with 25 the screw shell of the lamp socket or equivalent fitting into which the plug is inserted, thereby eliminating danger of the fastening becoming loosened, while at the same time materially enhancing the general structural 30 features of the plug from a practical and serviceable standpoint.

With the above and other objects in view which will more readily appear as the description of the invention progresses, the 35 same consists in the novel construction shown in the accompanying drawings, in which:—

Figure 1 is a vertical sectional view of a plug embodying the present improvements.

Fig. 2 is a vertical sectional view taken at right angles to Fig. 1.

Fig. 3 is a perspective view showing the parts prior to assembly.

Similar references designate corresponding parts throughout the several figures of the drawings.

The present improvements are susceptible of embodiment in attachment plugs of the 50 usual type which include a plug body 1 and a detachable contact carrying cap member 2. In this respect the invention involves no departure from the general type of devices of the class to which it belongs. The said 55 plug body 1 is however, preferably pro-

vided with the longitudinal openings 3 and 4 for receiving the contact blades 5—5 of the cap, and is also provided at one end with a central upstanding knob portion 6 which is countersunk as at 7 to receive the head of 60 a fastening screw 8 that extends through the opening 9 in the axis of the body to receive a holding nut 10 located in the recess 11, for the purpose of securing the center contact member 12 to the plug body. The 65 spring body portion of the center contact member 12 is preferably arranged in the opening 4 of the body as shown in Fig. 1, and the end fastened by the screw 8 constitutes one of the plug terminals for engaging 70 with the center plug contact of the lamp socket or equivalent electrical fitting into which the plug is inserted.

The novel and distinctive feature of the present invention resides in the manner of 75 securing the screw shell contact member 13 and the plug terminal 14 in position, and to this end it is proposed to provide the rim of the plug body surrounding the knob 6 at diametrically opposite points with the tu- 80 bular rivets or equivalent fastenings 15, the same being preferably molded in the plug body at the time of manufacture. The screw shell 13 is provided with the ear portions 13^a for engaging over the rivets 15, and 85 because of the spacing and arrangement of the latter it will be apparent that relative rotation between the shell and the plug body is prevented, the twisting strain or torque 90 being readily absorbed by the two rivets and distributed in such a manner as to be effectively neutralized.

After the perforated ears of the screw shell contact have been fitted over the rivets, the perforated portions 14^a at the extremities of the horseshoe-shaped portion of the terminal 14 are also placed over the rivets, whereby when the upper ends thereof are upset by spinning, mashing or an equivalent operation, the shell 13 and terminal 14 100 will be rigidly secured to the plug body, and also to each other thereby establishing a positive electrical contact between the shell and the terminal in a safe and practical manner.

By reason of the rivets being firmly anchored in the plug body 1, the same constitute in effect a rigid part of the plug itself, and thus are of maximum efficiency as holding elements for the shell 13 and ter- 110

minal 14 when flanged or headed in the well-known manner. Furthermore, owing to the fact that these rivets are located at the end of the plug they greatly facilitate the assembling of the shell with reference to the plug body and the horseshoe terminal element with reference to the shell, and when the plug is inserted in a receptacle the flanged ends thereof will not in any way hinder the engagement between the plug and the receptacle because of the fact that the said flanged ends will lie in the space between the end of the center contact and the plane of the shoulder or rim of the plug body, which space is necessary for insulating purposes.

For the purpose of providing additional union between the plug body and the shell, the same may be provided with the circumferential groove G whereby the edge 13^b of the shell may be pressed therein by spinning or a like operation. This additional engagement between the shell and the plug body has the effect of stabilizing the relatively thin metal shell 13 on the body and provides a neat and attractive finish between the shell and the body adjacent the cap end of the latter.

From the foregoing it will be apparent that the distinctive feature of the present invention resides in the provision of anchors carried by the plug body parallel to the axis for the purpose of facilitating the assembly of the screw shell contact and one of the plug terminals for securing the same in position.

Another novel feature of the present invention is found in connection with the plug terminal contact members 12 and 14. The body portion of each contact is preferably in the form of a flat spring strip x, provided with the pressed-out holding boss y and adapted to be so mounted on the plug as to be obliquely disposed in the openings 3 or 4. The relatively free end of the flat spring strip is provided with the angularly disposed tip portion z which is adapted to engage with the wall of the opening opposite that engaged by the base of the spring strip. The effect of this oblique disposition of the spring strip in a passageway or open-

ing in the plug body is to provide a converging guideway between the spring strip and the walls of the plug body which are engaged by the blades 5—5, and because the angularly disposed tip portion z abuts with the opposite wall of the passageway, greater stiffness is imparted to the spring body which has the effect of rendering the engagement of the holding boss y with the opening or equivalent keeper elements 5^a in the blades more positive to prevent accidental withdrawal of the said blades. In other words the intermediate portion of the spring strip which carries the holding boss 65 has a greater locking effect by reason of the abutment of the tip portion z with the wall of the opening as described, so that a relatively light spring strip will have the same holding effect as a strip of much 70 heavier gage.

Without further description it is thought that the many features and advantages of the present invention will be readily apparent, and it will also be understood that 75 various changes in the form, proportion, and minor details of construction may be resorted to without departing from the spirit of the invention or scope of the appended claim.

I claim:—

In an attachment plug, means for uniting the cap and body including in combination with the body having parallel blade receiving openings therein, of spring contact 85 members mounted in each opening and obliquely disposed therein whereby their relatively free ends engage the outer sides of the opening, said springs also having a holding portion disposed toward the inner 90 wall of the opening, and a cap carrying a pair of spaced contact members adapted to slidably engage the inner walls of the openings in the body and having keeper elements for receiving the holding portions 95 of the springs.

In testimony whereof I hereunto affix my signature in the presence of two witnesses.

EDGAR H. FREEMAN.
